CLAIM

The ornamental design for a toner container for a copying machine, as shown.

DESCRIPTION

FIG. 1 is a front elevational view of a toner container for a copying machine, showing my new design;
FIG. 2 is a right side elevational view thereof;
FIG. 3 is a rear elevational view thereof;
FIG. 4 is a top plan view thereof;
FIG. 5 is a bottom plan view thereof;
FIG. 6 is a side elevational view thereof;
FIG. 7 is an enlarged cross-sectional view thereof, taken along line 7—7 of FIG. 6;
FIG. 8 is an enlarged cross-sectional view thereof, taken along line 8—8 of FIG. 1; and,
FIG. 9 is a top plan view thereof showing the toner container with its cover opened.

FIG. 1

FIG. 2

FIG. 3

FIG. 4

FIG. 5

FIG. 6

FIG. 7

FIG. 8

FIG. 9
